J. R. HENDERSON

PARTICLE WARDROBE

Filed Dec. 4, 1923

UNITED STATES PATENT OFFICE.

JOHN R. HENDERSON, OF HAMLET, NORTH CAROLINA.

PORTABLE WARDROBE.

Application filed December 4, 1923. Serial No. 678,543.

To all whom it may concern:

Be it known that I, JOHN R. HENDERSON, a citizen of the United States, residing at Hamlet, in the county of Richmond and 5 State of North Carolina, have invented new and useful Improvements in Portable Wardrobes, of which the following is a specification.

This invention relates to improvements in 10 portable wardrobes, and particularly to a combined portable wardrobe and shelf.

One object of the invention is to provide 15 a portable wardrobe and shelf which may be hung from a wall or other surface at any point desired for use, removed therefrom for use in any other place, and folded in compact form so as to be readily and conveniently transportable.

Another object of the invention is to provide 20 a portable wardrobe which when folded may be secured in compact condition, together with all the appurtenances thereof.

Still another object of the invention is to provide 25 a portable wardrobe the shelf member of which carries upon the underside thereof garment suspending means, together with means for hanging a curtain so as to conceal the suspending means and the garments suspended therefrom, said suspending means being of a type admitting of 30 the ready and convenient application and removal of the curtains and their adjustment to closed and opened positions, and which further embodies novel means for 35 concealing such suspending means from view and at the same time enclosing and protecting the hung edges of the curtains.

The invention consists of the features of 40 construction, combination and arrangement 45 of parts, hereinafter fully described and claimed, reference being had to the accompanying drawing, in which:—

Figure 1 is a front elevation, partly in 45 section, of a portable wardrobe embodying my invention as it appears when suspended for use.

Figure 2 is a sectional view on the line 2—2 of Figure 1.

Figure 3 is a sectional view on the line 50 3—3 of Figure 1.

Figure 4 is a perspective view of the device in outfolded condition and with the curtains removed.

Figure 5 is a similar view of the device 55 in inverted position.

Figure 6 is a view of the device as it appears when folded for storage or transportation.

In carrying my invention into practice I provide a portable wardrobe comprising a back section 1 and a shelf section 2, the said section 2 being hinged at its rear edge to the lower edge of the section 1, as indicated at 3. This hinge connection adapts the shelf section 2 to be folded down at 60 right angles to the back section 1 or to be folded up against the same in parallel relation therewith. The hinges 3 are applied to the section 2 just in advance of the rear edge thereof, so that when said section 2 65 is swung down to a horizontal position its rear edge will engage under the lower edge of the section 1, to assist in bracing the section 2 to sustain the weight of the garments and curtains suspended thereby. The 70 back section 1 is adapted to be secured to a wall or other supporting surface 4 in any suitable manner. As shown in the present instance said section 1 may be provided with a central opening 5 to receive a suspending 75 hook 6 driven into the wall 4, or said section 1 may be provided at suitable points with openings 6' through which nails or other fasteners may be driven to pierce the wall and thereby suspend the wardrobe 80 therefrom. Chains or other flexible bracing members 7 are provided to further assist in supporting the let-down shelf 2 and the clothes or curtains suspended therefrom. These connections 7 are secured at one end 85 to screw eyes or the like 8, fixed to the back section 1 and are provided at their free ends with snap hooks 9 to engage screw eyes or the like 10 on the shelf section 2. Openings 11 are provided in the back section 1 adjacent to the screw eyes 8, through 90 which openings the eye members of the screw eyes 10 are adapted to pass when the shelf section 2 is folded against the back section 1. In this folding operation, the snap hooks 9 are disengaged from the screw eyes 10, and the shelf section 2 folded against the back section 1 so that the eye portions of the screw eyes 10 extend through the openings 11 and are exposed at the rear 95 of the section 1, whereby suitable fastening members may be passed through the screw eyes 10 to hold the device in folded position.

For this purpose, as shown in present instance, hinged hooks 12 are provided on 110

the rear surface of the back section 1, as shown particularly in Figure 6. Recesses 11' in the shelf section receive the screw eyes 8 when the parts are folded, allowing 5 them to fold close together.

- The shelf section 2 is provided on its underside with a looped suspending member 13, which extends in a direction transversely of the same, or from front to rear thereof. 10 One or more of these devices 13 may be provided, with which clothes hangers or the like may be engaged for suspending articles of clothing from the shelf section. A curtain made in two sections 14 and 15 is provided 15 for concealing the clothing or other articles suspended from the shelf portion and to protect the same from dust, etc., as well as to form a complete enclosure of presentable type. These curtain sections are secured to 20 the shelf by curtain suspending means comprising front corner hooks 16, an intermediate front hook 17 and rear corner hooks 18 and 19, together with a wire or other flexible suspension line 20 and a cleat or 25 other anchoring member 21 positioned adjacent to the hook 19. The curtain sections 14 and 15 are provided at their upper edges with hems or loops 22 through which the suspending line 20 may be passed, such hems 30 or loops being cut away at the points 23 so that portions of the line may be exposed to engage the front corner hooks 16. After the line is threaded through the hems of the curtain sections, one end of the line is engaged 35 with the hook 18, and then the line is extended around close to and parallel with the sides and front edges of the shelf section and engaged with the hooks 16, 17 and 19 and its free end finally engaged with the cleat or 40 anchoring member 21, whereby the suspending line is securely fastened in position for supporting the curtains but may be removed in a practically instantaneous manner for the detachment of the curtains. Hence the 45 curtains may be applied in a ready, quick and convenient manner and as readily removed for cleansing or repairs or to adapt them to be folded for storage or transportation as hereinafter described.
- 50 An important feature of my invention resides in the fact that the section 2 when arranged in operative position is not only adapted for use as a shelf for supporting various articles upon its upper surface, but 55 embodies suspending means for the clothes and curtains which are wholly concealed from view and protected from injury. This advantage is secured by the use of the curtain suspending means of the type described.
- 60 In addition I also provide the shelf section 2 with strips 24 extending around its front and end edges, which strips provide a depending rim or valance around the suspending members and upper edges of the curtains, concealing the same from view so that 65

no unsightly portions appear, and at the same time protecting the suspended edges of the curtains and their suspending means from liability of injury by contact with extraneous objects. It is not therefore necessary to make the hemmed edges of the curtains of ornamental type; and by arranging them as described they will be protected to a great degree from injury or wear. 70

It will be understood that the invention 75 provides a portable wardrobe of especial advantage for the use of those desiring to hang garments or the like in rooms, offices or houses where there are no cupboards, or whenever it is desired to hang garments or 80 the like at points where cupboard or wardrobe space is not accessible, and such device may be removed from place to place for use wherever desired. Whenever the device is taken down for storage or transportation, it 85 may be folded in close compass for such purpose by releasing the curtains and storing them in folded condition between the folded back and shelf sections 1 and 2, which will be secured in folded position by the fasteners 10 and 12, permitting ready transportation of the device with all its parts contained against any possibility of damage or loss. When the device is so folded, it will 90 be understood that the suspending member 95 13 forms a convenient handle for its transportation or for suspending it in an out of the way position from any support. When the device is in use it serves, as stated, a variety of purposes and its curtains 14 and 15, which may be of any desired length and as plain or ornamental as desired, effectually conceal the garments from view and protect them from dust or possible injury. Other 100 advantages of the invention will be apparent from the foregoing description. 105

Having thus fully described my invention, I claim:

1. A portable wardrobe comprising a back section, a shelf section hinged thereto, said back section having openings extending therethrough, fastening eyes on the shelf section adapted to project through said openings when said shelf section is folded, flexible eyes on the back section, suspending chains secured at one end to the fastening eyes on the back section and having hooks at their free ends for detachable engagement with said fastening eyes on the shelf section, garment suspending means carried by the shelf section, and fastening members on the rear face of the back section for engagement with said fastening eyes on the shelf section, when said eyes are extended through the openings in the back section, for securing said back section and said shelf section in folded relation. 110
2. A portable wardrobe comprising an oblong rectangular back section, an oblong rectangular base section hinged at its rear 115

120

125

130

edge to the back section adjacent to the lower edge thereof, said back and base sections being of substantially the same superficial dimensions and adapted to fall with 5 their edges in substantial alinement, the said back section being provided with openings therein, screw eyes on the back section adjacent to said openings, screw eyes on the base section, bracing chains extending between the eyes on the base and back sections, the eyes on the base section being adapted to extend through the openings on

the back section so as to be exposed at the rear of said back section when the two sections are folded together, suspending means 15 on the underside of the base section, and fastening hooks on the rear face of the back section adapted to be engaged with the screw eyes on the base section when said base section is folded against the back section so 20 as to fasten the two sections in collapsed condition.

In testimony whereof I affix my signature.
JOHN R. HENDERSON.
